DESIGN FOR A DISPLAY FIGURE OR ANALOGOUS ARTICLE

Elsie Krummeck, Brooklyn, N. Y., assignor to
J. H. Lester & Co. Incorporated, New York,
N. Y., a corporation of New York

Application April 28, 1936, Serial No. 62,351

Term of patent 3½ years

To all whom it may concern:

Be it known that I, Elsie Krummeck, a citizen of the United States, residing at 211 Ridgewood Avenue, Borough of Brooklyn, county of Kings, city of New York, and State of New York, have invented a new, original, and ornamental Design for a Display Figure or Analogous Article, of which the following is a specification, reference being had to the accompanying drawing, forming a part thereof.

I claim:

The ornamental design for a display figure or analogous article as shown.

In testimony whereof I have signed this specification.

ELsie KRUMMECK.
